(57) CLAIM

The ornamental design for a sing-along stand, as shown and described.

DESCRIPTION

FIG. 1 is a perspective view of a sing-along stand illustrating the new design;

FIG. 2 is an enlarged front view thereof;

FIG. 3 is a rear view thereof;

FIG. 4 is a right side view thereof, the left side view is a mirror image of the right side view;

FIG. 5 is a top plan view thereof; and,

FIG. 6 is a bottom plan view thereof.

The broken line showing on the drawing disclosure is for illustrative purposes only and forms no part of the claimed design.
